UNITED STATES PATENT OFFICE.

DEWEY SHAY, OF SPOKANE, WASHINGTON.

TIMING AND DISTRIBUTING DEVICE.

Application filed March 8, 1926. Serial No. 93,312.

- This invention relates to an improved distributor and timer for internal combustion engines and seeks, among other objects, to provide a device of this character where-
 5 in the functioning of the device may be readily observed while the device is in operation so that failure of any of the working parts of the device may be readily located.
- 10 The invention seeks, as a further object, to provide a device of such simplicity of construction that the average motorist may, without disturbing the timing, readily correct fault in the device.
- 15 Still another object of the invention is to provide a device so constructed that the various parts may, without disturbing the timing, be readily removed for repairs. And the invention seeks, as a still further
 20 object, to provide a device well adapted for general use, which will be dependable in operation, and wherein provision will be made for necessary adjustments to maintain the proper functioning of the device.
- 25 Other objects of the invention not specifically mentioned in the foregoing will appear during the course of the following description.
- In the accompanying drawings:
 30 Figure 1 is a top plan view of my improved distributor and timer showing the manner in which the working parts of the device may be observed through the transparent cover employed.
- 35 Figure 2 is a transverse sectional view on the line 2—2 of Figure 1, looking in the direction indicated by the arrows. Figure 3 is a detail elevation showing the stop posts employed for limiting the rotation
 40 of the timer casing to vary the instant of firing.
- 45 Figure 4 is a detail sectional view on the line 4—4 of Figure 1, looking in the direction indicated by the arrows. Figure 5 is a detail sectional view on the line 5—5 of Figure 1, looking in the direction indicated by the arrows, and particularly showing the mounting of the breaker arm.
- 50 Figure 6 is a detail sectional view on the line 6—6 of Figure 1, looking in the direction indicated by the arrows, and particularly showing the arm provided to receive a hand control rod for rotating the casing.
- 55 Referring now more particularly to the drawings, the numeral 10 indicates a sta-
 tionary supporting sleeve which may be formed in any approved manner for rigid attachment to the engine in connection with which the device is used. Journaled through
 60 the sleeve is a timer shaft 11 provided near its upper end with a conical portion 12 and terminating in a stud 13. This shaft may be connected with the engine crank shaft or other driving element of the engine in any
 65 approved manner, to be rotated at half the speed of the crank shaft, but since the driving connection between said element and the shaft 11 forms no part of the present invention, it has not been shown. Formed in
 70 the upper end of the sleeve 10 to surround the shaft 11 in concentric relation, is a socket 14.
- Rotatably mounted upon the sleeve 10 is a preferably cylindrical casing including
 75 a metallic bottom plate 15 to which is attached a shell 16 of suitable insulating material. As shown in Figure 2, the plate 15 is provided with a peripheral upstanding flange 17 while the shell 16 is cut away externally at its lower margin to snugly accommodate said flange and is provided with an overlapping flange 18. Extending through said flanges at suitably spaced
 80 points about the casing are cap screws 19
 85 rigidly securing the shell upon the bottom plate. This construction is of advantage when repairs are necessary since, by displacing the screws 19, it is possible to remove the shell and the parts attached thereto as
 90 a unit. Preferably, the shell and bottom plate are provided with suitable locating marks so that the shell may, with facility, be correctly reassembled with the bottom plate. Formed on the bottom plate 15 centrally thereof is a boss 20 which seats flat
 95 against the upper end face of the sleeve 10, and depending from said boss is an annular flange 21 rotatably fitting in the socket 14, the coaxing faces of the bottom plate and
 100 sleeve being smoothed so that the casing may freely turn upon the sleeve. Fitting through the bottom plate from the inner side thereof is a bushing 22 for the shaft 11, which is snugly received within the flange
 105 21 of the bottom plate and terminates flush therewith. At its upper end, the bushing is provided with an annular flange 23 which overhangs the bottom plate, and screwed into
 110 said plate is a pin 24, the upper end of which is snugly received in a recess in said flange for locking the bushing against rotation.

Fixed to the bottom plate 15 is a radially projecting arm 25, apertured, as seen in Figure 1, to receive a control rod or the like, so that the casing of the device may be turned to advance or retard the instant of firing. Fixed to the sleeve 10, as best seen in Figure 3, is a stop arm 26 and projecting from the boss 20 of the bottom plate are spaced pins 27 to selectively engage said arm for limiting the turning movement of the casing.

Extending through the bottom plate 15 near the periphery thereof is an insulating bushing 28, and resting against this bushing is a post 29 having a stem 30 extending through the bushing, the bushing being provided at its upper end with a relatively large flange for effectually insulating the post with respect to the bottom plate. Freely surrounding the stem 30 to rest against the lower side of the bottom plate is an insulating washer 31 and screwed on said stem is a nut 32 rigidly binding the post in position. The stem 30 provides a terminal for a primary low tension circuit wire 33, and securing the wire upon the stem is a thumb nut 34. As shown in Figure 1, the post 29 is flat, and screwed through the post is a breaker terminal 35. Thus, as will be seen, said terminal may be readily adjusted upon the post, and screwed on said terminal to abut opposite sides of the post are lock nuts 36 for securing the terminal in adjusted position.

Pressed through the bottom plate 15 in spaced relation to the bushing 28, as particularly seen in Figure 2, is a metallic bushing 37, and resting at one end upon said bushing is a breaker arm 38 having a convex inner side face shown in Figure 1. Extending through the inner end of said arm and through said bushing is a pivot pin 39, seen in Figure 5, swingingly mounting the arm, the pin being provided at its upper end with a head 40. Screwed or otherwise secured at its smaller end to the upper face of the arm 38 is a spring clip 41, the larger end of which is cupped to fit over the head 40 of the pin. Thus, the clip will prevent upward displacement of the pin independently of the arm while, however, as will be seen, by lifting upwardly on the arm, the pin may be withdrawn and the arm removed. Extending through the free end of the arm is a breaker terminal 42 to coact with the terminal 35, and screwed on the rear end of the terminal 42 is a nut 43 rigidly connecting said terminal with the breaker arm. Fitting over the tapered portion 12 of the shaft 11 is a cam 44 which is clamped on the shaft by a nut 45 screwed on the stem 13. As will be observed, the head of the bushing 37 is thickened to support the breaker arm 38 in a plane with the cam so that the cam will 65 coact with the convex inner side face of

said arm. In the present instance I have shown a six pointed cam, the illustrated device being designed for use in connection with a six cylinder engine. However, in any instance where the device is to be employed in connection with an engine having either a greater or less number of cylinders, the cam will, of course, be provided with a corresponding number of points. Resting on the bottom plate 15 forwardly of the breaker arm 38, is a post 46 secured to the bottom plate by a pair of screws 47, as seen in Figure 4, and extending freely through the post is an eye bolt 48 carrying a nut 49. Suitably anchored at one end to the free end portion of the breaker arm is a spring 50, the opposite end of which is engaged with the eye of the bolt 48. Thus, this spring will normally hold the terminal 42 of the breaker arm in engagement with the terminal 35 for closing the primary low tension circuit, said circuit being electrically grounded through the breaker arm and bottom plate 15 to the sleeve 10. As the shaft 11 revolves, the cam 44 will intermittently swing the breaker arm for breaking said circuit and should the spring 50 become weakened, the tension of the spring may be readily adjusted by adjustment of the nut 49. Furthermore, by removing the nut 45 and loosening the cam 44 on the shaft 11, the cam may be readily rotated relative to the shaft for adjusting the timing, when the nut may be again applied and tightened for clamping the cam in fixed position upon the shaft. Resting upon the bottom plate 15 behind the post 46 is an appropriate segmental condenser 51, one edge of which is curved to fit the flange 18 of the shell 16, and extending from the ends of the condenser are lugs 52 fixed to the bottom plate by screws 53 for securing the condenser in position. Extending from one side of the condenser is a lead 54 clamped to the post 29 by a binding screw 55, and extending from the other side of the condenser is a ground lead 56 secured to the bottom plate 15 by a screw 57. Thus, as will be well understood, the condenser will function to reduce the tendency toward arcing between the terminals 35 and 42 of the breaker.

Extending freely through the shell 16 at equally spaced points are radial terminals 58 which, as seen in Figure 2, are provided near their inner ends with collars 59 abutting the inner face of the shell, and screwed on the outer end portions of said terminals are nuts 60 rigidly securing the terminals in position. These terminals also carry thumb nuts 61 for connecting the spark plug leads, indicated at 62, with said terminals, and frictionally fitting over the outer ends of the terminals are preferably rubber caps 63 for excluding moisture. In the present instance, I have shown the use of six of the 130

terminals 58 but, of course, the number of said terminals will be determined by the number of cylinders of the engine in connection with which the device is used. Connected with the shaft 11 to cooperate with said terminals is a distributor rotor including a head 64, and fixed to said head is a radial electrode 65 lying in a plane with said terminals 58. The head 64 of the rotor is formed of suitable insulating material and, as seen in Figure 2, is provided with a recess 66 to freely accommodate the nut 45 on the shaft 11. Extending upwardly from said recess is a bore 67 snugly receiving the stud 13 of the shaft, the head resting on the cam 44. Thus, the stud 13 will rigidly center the head with respect to the shaft, and screwed into the cam 44 is an upstanding pin 68 snugly received in a suitable recess 15 in the head for locking the head to turn in unison with the cam and with the shaft 11. However, as will be seen, the head may be lifted from the shaft for removing the rotor. The electrode 65 is secured to the head 20 by a pair of screws 69, and formed on said electrode at its free end is a widened thickened terminal 70, which, as seen in Figure 2, is disposed to pass the inner ends of the terminals 58 in close spaced relation thereto to 25 produce a spark gap between the electrode and each of said terminals successively. The terminals 58 may be adjusted with respect to the electrode by inserting one or more shims behind the collars 59 of the terminals 30 and should it become necessary to renew the terminals, said terminals may be readily removed. By widening the terminal 70 of the electrode 65, proper functioning of the device is insured even though the setting 35 of the timing is a little early or a little late, and, preferably, the terminal 70 is, as seen in Figure 1, provided centrally with an arrow 40 which will be found of assistance in positioning the rotor with respect to any one 45 of the terminals 58, when setting the timing.

Countersunk in the upper edge of the shell 16 to lie flush therewith is a transparent cover 71 for the casing. This cover may be formed of any approved transparent material, and securing the cover in position are diametrically arranged thumb screws 72 beneath which are clamped washers 73 overlying the peripheral margin of the cover. Mounted upon the cover, in axial alignment 50 with the shaft 11, is a post 74 having a stem 75 which extends freely through the cover, and loosely fitting on the stem to overlie opposite sides of the cover are preferably fiber washers 76. Screwed on the outer end portion 55 of the stem is a nut 77 clamping the post upon the cover while at the upper end of said stem is a thumb nut 78 for connecting a secondary high tension circuit lead 79 with

said post. Secured to the electrode 65 by the pair of screws 69 is a contact spring 80 which extends upwardly over the head 64 of the distributor rotor and is formed with a spherically curved head to seat in the cupped inner end of the post 74 for electrically connecting the electrode with said post. Thus, as will be well understood, when the primary circuit is broken by movement of the breaker arm 38, current will flow in the secondary circuit through the electrode 65 to one of the terminals 58 and thence to a corresponding spark plug of the engine. Screwed or otherwise secured to the head 64 of the distributor rotor is a counterweight 81 for said rotor.

As will now be seen, by looking through the cover 71, the functioning of the device may be observed while the device is in operation. Thus, any fault existing in the device may be readily located. Furthermore, by displacing the cover, the working parts 85 of the device may be readily removed for repair and, with the exercise of ordinary care, replaced without disturbing the timing of the device.

Having thus described the invention, what I claim is:

1. A device of the character described including a sleeve having a socket in its upper end, a casing having a boss on its under side seating on the end of the sleeve and 95 having an annular flange fitting in said socket, a timer shaft journaled through the sleeve and extending into the casing, circuit breakers within the casing operated by rotation of the timer shaft, means for rotating the casing, a stop arm on the sleeve projecting over the side of the boss, and stops on the boss at opposite sides of said arm for limiting the rotation of the casing in opposite directions. 100

2. A device of the character described including a casing having a bottom plate, a timer shaft extending through said plate into the casing, a primary circuit post mounted upon and insulated from the bottom plate, a terminal carried by said post, a bushing carried by the bottom plate, a spring pressed breaker arm resting at one end upon the bushing and provided near its opposite end with a terminal to cooperate with the first-mentioned terminal, a smooth pivot pin extending through the supporting end of the arm and the bushing, means carried by the arm to engage the pin for holding the pin against upward displacement independently 115 of the arm, the pin being removable from the bushing with the breaker arm, and means whereby rotation of the shaft will effect 120 rocking of the arm.

In testimony whereof I affix my signature.
DEWEY SHAY. [L. s.]
